DOG BED

Betty L. Bloyd, Phoenix, Ariz., assignor to Harry Carr, Phoenix, and Cletus Caroland, Mesa, Ariz., fractional part interest to each

Filed Mar. 2, 1973, Ser. No. 337,756

Term of patent 14 years

Int. Cl. D30—06

U.S. Cl. D30—41

fig. 1

fig. 3

fig. 2

fig. 4

FIG. 1 is a perspective view of a dog bed showing my new design with the closure flap partially turned back; FIG. 2 is a top plan view;

FIG. 3 is a front elevational view with the closure flap in a closed position; and

FIG. 4 is a right side elevational view.

I claim:

The ornamental design for a dog bed, as shown and described.
